BRICK WALL SETTING DEVICE FOR CESSPOOLS

Raymond F. Smith, Fresno, Calif., assignor to Smith and Yearout, Fresno, Calif., a partnership

Application October 16, 1953, Serial No. 386,470

4 Claims. (Cl. 294—67)

This invention is directed to, and it is an object to provide, a novel device for supporting, lowering, and setting a complete cylindrical brick wall which forms the lining of an underground cesspool.

Another important object of the invention is to provide a device, for the purpose described, which is operative to set a cylindrical brick wall in a cesspool hole, which frequently is relatively deep, without the necessity of a worker entering the hole during the operation; this being of substantial advantage, as the safety of the workers is materially increased.

A further object of the invention is to provide a device, for the purpose described, which is useful to set a cylindrical brick wall in a cesspool hole in a rapid, accurate, and effective manner.

Another object of this invention is to provide a brick wall setting device, for cesspools, which includes a novel platform unit adapted to be lowered progressively into a cesspool hole; the cylindrical wall being laid course by course on the platform unit from above ground, and when the wall is complete and fully lowered into the hole the device is operative to release the wall onto the bottom of the hole, whereupon said device is withdrawn upwardly through the wall to an above-ground or clearance position.

It is also an object of the invention to provide a brick wall setting device, for cesspools, which is of simple but rugged structure; being designed for ease and economy of manufacture and convenience of use.

An additional object of the invention is to provide a practical and reliable brick wall setting device for cesspools, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of the device in substantially its starting position in alignment with a preformed cesspool hole in the ground.

Fig. 2 is a similar view, but shows the device lowered part way into the cesspool hole, and with the device supporting the cylindrical brick wall.

Fig. 3 is likewise a similar view, but shows the device in its fully lowered position and released, with the brick wall in final position seating on the bottom of the cesspool hole.

Fig. 4 is an enlarged plan view of the platform unit; the suspension rods and the bail being broken away.

Fig. 5 is a fragmentary sectional elevation on line 5—5 of Fig. 4, showing—in full lines—one of the foot plates, and related mechanism, in the normal or wall supporting position, and—in dotted lines—in released position.

Referring now more particularly to the drawings and to the characters of reference marked thereon, the device comprises a platform unit, indicated generally at 1; such unit including a circular, horizontal platform 2 formed with an upstanding peripheral flange 3. The platform 2 is of somewhat lesser diameter than the diameter of the

2

preformed, cylindrical cesspool hole 4 in which a continuous or cylindrical brick wall 5 is to be set in substantially matching relation.

A plurality of circumferentially spaced, upwardly converging suspension rods 6 are fixed to the top of the platform 2 adjacent its periphery, and at their upper ends said rods 6 are secured to the lower block 7 of an upwardly extending block and tackle unit, indicated generally at 8. The block and tackle unit 8 is connected to, and depends from, a portable gantry or the like (not shown) which is erected in an upstanding position above the cylindrical cesspool hole 4.

A plurality of normally horizontal foot plates 9 rest on the outer portion of the circular platform 2 in equidistantly circumferentially spaced relation; such foot plates 9 being of a length such that they project a distance beyond the peripheral flange 3 substantially equal to the horizontal thickness of the arcuate segmental bricks 10 which comprise each course 11 of the cylindrical brick wall 5.

The corresponding bricks 10, in adjacent courses 11 of the cylindrical brick wall 5, are disposed in half lapping relation, as shown, and said bricks—as is conventional—each include lateral, outwardly and downwardly inclined

25 drain holes 12 therethrough.

The normally horizontal foot plates 9 project in relatively loose-play relation through downwardly opening notches 13 in the lower edge of the peripheral flange 3, and additionally—in communicating relation with the 30 notches 13—the platform 2 is radially slotted, as at 14, with the slots of a length and width to permit said foot plates 9 to swing from a horizontal position, as in full lines in Fig. 5, to a vertical position, as in dotted lines in said figure.

35 As the foot plates 9 so swing they move downwardly and inwardly at the free end portion, whereby when they reach vertical they are disposed wholly inwardly of the periphery of platform 2.

In order to support the foot plates 9 in their normal 40 horizontal position, yet permit them to swing as above without displacement from the platform 2, each of said foot plates has a cross rod 15 fixed on top thereof and projecting beyond the side edges; the projecting end portions of each cross rod 15 bearing on top of the platform 2. The cross rods 15 have a slight bend, which normally extends inwardly, at the ends in order to permit them to lie relatively close to the flange 3.

Locator blocks 16 upstand from the platform 2 on each side of the foot plates 9 inwardly of the cross rods 15 50 whereby to further assure of the maintenance of proper positioning of said foot plates but without limiting the hereinbefore described swinging thereof from horizontal to vertical position.

The foot plates 9 are each normally maintained 55 against such swinging motion by means of a pivoted catch 17 which engages over the rear end of each foot plate; each catch 17 including an ear 18 which depends through a radial slot 19 in the platform 2, and below said platform the ear is turnably supported on a fixed cross pin 20 welded to the under side of the platform 2 and spanning the related slot 19.

A relatively short post 21 is fixed to, and extends from, the center of the platform 2, and a sleeve 22 is slidably disposed on the post 21.

60 A plurality of links 23 in spider arrangement are pivotally connected between attachment ears 24 on the sleeve 22 and the corresponding catches 17.

The sleeve 22 is normally in its lowered position, at which time the links 23 are slightly below dead-center 70 maintaining the catches 17 in positive engagement over the rear ends of the foot plates 9.

The sleeve 22 is fitted, at the top, with an upstanding

bail 25 to which a pull cord 26 is connected; said pull cord being of a length to extend upwardly some distance.

In use of the above described device it is suspended initially in the position shown in Fig. 1, with the sleeve 22 lowered so that the catches 17 maintain the foot plates 9 in their normal horizontal position projecting beyond the peripheral flange 3.

Thereafter, the cylindrical brick wall 5 is laid course by course; the lower course being laid on and supported by the foot plates 9. Each foot plate 9 engages centrally under the corresponding brick 10 of said lower course. The upstanding peripheral flange 3 serves as an annular guide against which the lower course 11 of bricks 10 is laid, whereby such course is true-circle, which in turn gives an accurate pattern for the subsequently laid courses.

As the cylindrical brick wall 5 is built up course by course from above ground, the platform unit 1 is progressively lowered into the cesspool hole 4 by means of the block and tackle unit 8.

Upon the platform unit 1 reaching the bottom 27 of the cesspool hole 4, the cylindrical brick wall 5 has been completed and lies within the cesspool hole in substantially matching relation and extending from top to bottom thereof.

Thereupon the cord 26—which reaches to above ground—is pulled upwardly, which slides the sleeve 22 in a corresponding direction on the post 21. When this occurs the links 23 are correspondingly raised at their inner ends, breaking upwardly above dead-center and assuming an outward and downward incline. This causes retraction of the catches 17. Nextly, the block and tackle unit 8 is worked in a manner to begin upward raising of the platform unit 1, whereupon the foot plates 9 are caused to swing relatively downwardly and inwardly at their outer end portions, digging into the soft earth at the bottom 27 of the cesspool hole 4. When such swinging of the foot plates 9 occurs they free from the lower end of the cylindrical brick wall 5 and assume their vertical position, whereupon with continued upward raising of the platform unit 1 they form no obstruction, and such unit can be readily withdrawn from the cylindrical brick wall 5 to a clearance position thereabove.

With the above described device a cylindrical brick wall 5 can be readily manually laid from an above-ground position, and such wall progressively lowered into the cesspool hole 4 and seated on the bottom thereof; all without the necessity of a worker entering the hole during the operation. The device therefore not only provides for greater safety to the workers, but permits of the laying of a brick wall in a cesspool hole in a rapid and expeditious manner.

From the foregoing description it will be readily seen that there has been produced such a device as will substantially fulfill the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following is claimed as new and useful, and upon which Letters Patent are desired:

1. A device, for lowering a brick wall into and setting the same in a cesspool hole, comprising a platform adapted for entry into a preformed cesspool hole, means suspending the platform for lowering the same into the cesspool hole from top to bottom thereof, the platform including circumferentially spaced members having outer end portions radially out from the platform to support the wall from below for lowering into the cesspool hole, said members being movable from a wall supporting position to a released position inwardly of the wall so that the platform may be withdrawn upwardly without obstruction by said wall, control means to so move the members, releasable holding means normally preventing such movement of the members, and an annular flange supported by the platform and disposed radially inward of but adjacent said wall supporting portions of the members to locate and guide the lowest course of the wall when the latter is being placed on the device.

2. A device, for lowering a brick wall into and setting the same in a cesspool hole, comprising a platform adapted for entry into a preformed cesspool hole, means suspending the platform for lowering the same into the cesspool hole from top to bottom thereof, wall supporting foot plates normally projecting outwardly from the platform in spaced relation about the same, means pivoting the foot plates intermediate their ends on the platform for swinging motion from said normal position to a released position inwardly of the wall, and releasable means normally preventing such movement of the foot plates; said last named means comprising catches normally engaging over corresponding foot plates at their inner end in holding relation, means pivoting the catches on the platform below the same, a central post upstanding from the platform, a sleeve slidable on the post, a pull member connected to and extending upward from the sleeve, and links, substantially horizontal when the catch is engaged, radiating from the sleeve and pivotally connected thereto and to the catches above the pivots thereof.

3. A device, as in claim 2, in which the links are below a dead-center position when the catches are engaged and the sleeve is fully lowered.

4. A device, for lowering a brick wall into and setting the same in a cesspool hole, comprising a platform adapted for entry into a preformed cesspool hole, means suspending the platform for lowering the same into a cesspool hole from top to bottom thereof, wall supporting foot plates normally projecting outwardly from the platform in spaced relation about the same, means pivoting the foot plates intermediate their ends on the platform for swinging motion from said normal position to a released position inwardly of the wall, and releasable means normally preventing such movement of the foot plates; said last named means comprising individual catches normally engaging over corresponding foot plates at their inner end in holding relation, means mounting the catches on the platform for releasing movement in a direction radially inward of the platform, and mechanism including a normally slack pull cable operable from above the hole and connected to the catches individually to release all said catches simultaneously.
